WILLIS C. WARD, OF ORCHARD LAKE, MICHIGAN

GRADER

Application filed November 26, 1928. Serial No. 321,934.

The invention relates to graders, more particularly designed for the smoothing and grading of vehicle roads, but also adapted for use in the grading or smoothing of golf courses, large lawns, etc. It is the object of the invention to obtain a construction which not only scrapes or planes off the humps and irregularities but also distributes the dirt thus removed so as to produce a smooth surface. To this end the invention consists in the novel construction as hereinafter set forth.

In the drawings:

Figure 1 is a plan view of my improved grader;

Figure 2 is a side elevation thereof;

Figure 3 is a similar view showing the operation of the grader in passing over uneven ground;

Figure 4 is an enlarged view of one of the hangers or supports for the grading blades and illustrates the manner in which said support may be accurately set as to height;

Figure 5 is an enlarged cross section through one of the forward or planing blades;

Figure 6 is a plan view of Figure 4.

My improved grader may be drawn by any suitable motive power, such as horses or a tractor or truck, preferably the latter. Essentially the construction comprises three sets of axles, A, B and C, mounted on suitable ground wheels D and connected to each other by reach frames. The axles A and B are connected through the V-shaped reach frame E having its forward end connected by the kingpin F and turntable G to the forward axle A and its rear or spread ends connected to the axle B. A similar reach frame E' is connected by a kingpin F' and turntable G' centrally to the axle B, while the rear or spread ends are connected to the axle C. There is also provision for pivotal action of the reach frames E and E' in a vertical plane which may be accomplished by attaching one of said frames such as the frame E to pivotal bearings H on the axle B. Thus with the construction as thus far described the axles are all free to move into different angular positions so as to facilitate the turning of the

machine and the reach frames E and E' are free to assume different angular positions in conformity to the contour of the ground.

Mounted beneath the reach frame E are planing blades I which are arranged to form a V with the apex pointed rearward and in the center of the vehicle. These blades I may be supported by vertically adjustable rod or hanger members J which engage suitable bearings on the reach frame. As shown, this reach frame is provided with cross bars K and K' which extend to suitable points for forming bearings to receive the hangers J, which hangers are connected near the forward and rear ends of the blades I. The blades I are preferably constructed as shown in Figure 5, being arranged at comparatively sharp angles in relation to the ground and having a sharpened forward and lower edge which acts as a cutting knife for slicing through humps or upward projections in the ground. Preferably the blade proper I is bolted or otherwise detachably secured to a supporting bracket member I' which in turn is secured to the hangers J. The rear end portions of the blades I are also preferably tapered or pointed so as to leave an opening through which the removed material may be deposited in a ridge in the center of the road.

Beneath the rear reach frame E' are supported spreader blades L which are joined together at their forward ends and at the center of the frame to form a plow and which inclines outwardly as they pass to the rear. The spreader blades L are so supported by hangers J' similar in construction to the hangers J and which are provided with like means for setting. This means specifically preferably is formed by a series of closely spaced holes J² placed in the hanger bar for engaging a cross pin J³ arranged above the bearing for the bar and limiting the downward movement thereof. Thus by shifting the pin J² this limit of downward movement may be adjusted as desired. Also the hangers at opposite ends of the blades may be independently adjustable so that the blade may be set at any angle desired. This is particularly useful where the road is to be crowned, as it enables the operator to set the blades

at any desired inclination. Also to facilitate such independent adjustment the hangers J' are pivotally attached to the blades as indicated at J⁴.

As has been stated the grader may be drawn by any suitable means such as the truck or tractor M which is coupled to a tongue N extending forward from the axle A. To enable the operator on the truck to control the blades and particularly to throw them out of action when so desired, I have arranged a mechanism for simultaneously raising all of the blades. This, as shown, consists in a series of rock levers O pivotally mounted on brackets O' on the reach frames and connected by links O² with the upper ends of the hangers J. Bell crank arms O³ project upward from the arms O and are connected to link rods P. These rods connect the bell crank arms for the forward and rear hangers of each blade, and in turn are connected by flexible link rods P' with the link rods for the hangers on the rear reach frame. The whole forms a system which when the forward bell cranks are actuated will simultaneously and similarly move all in rear. As shown, the forward bell crank levers are cross connected by a bar Q which in turn is connected with a cable R extending forward to the truck and then to a windlass S under the control of the operator of said truck.

With the construction as described, in operation the blades I and L may first be properly set according to the character of the work to be done, and as to whether the road is to be flat or crowned. The blades L will be set at a slightly higher elevation than the blades I so that the earth removed by the former will be distributed uniformly over the entire surface traversed by the blades. Thus with a single passage of the grader over the road, whatever material has been removed is again uniformly redistributed. If there are alternating hills or depressions in the road the grader is permitted to conform to these as each of the axles is free to rise or fall independently of the others. This results in holding the blades substantially parallel to the general contour of the road while permitting the levelling off of humps and distributing the material in the small depressions. When the direction of travel is changed the wheels of the rear axles will track those on the forward one, thereby causing the spreader plow to traverse the path of the planer blades. The earth removed by these planer blades is first directed to the center of the road where it is deposited in a ridge, but this ridge is levelled down by the distributor blades so as to be uniformly deposited over the entire width.

What I claim as my invention is:

1. A grader comprising forward, rear and intermediate wheeled axles, reach frames re-

spectively connecting said forward and rear axles with the intermediate axle and so as to provide pivotal connection between said frames, planer blades carried by the forward reach frame and spreader blades carried by the rear reach frame. 70

2. A grader comprising forward, rear and intermediate wheeled axles, reach frames respectively connecting said forward and rear axles with said intermediate axle and having therethrough a universal pivotal connection with each other permitting change of angular relation in both a vertical and in horizontal plane, a pair of planer blades carried by the forward reach frame and arranged in a V with the apex thereof pointing rearward to direct or remove material into the center of the path and spreader blades carried by the rear frame arranged as a V with its apex pointing forward, said blades 80 being adapted to uniformly distribute the material over the path. 85

3. A grader comprising forward, rear and intermediate wheeled axles, reach frames respectively connecting the said forward and rear axles with said intermediate axle and therethrough universally pivoted to permit independent angular adjustment in a vertical and in a horizontal plane, planer blades carried by said forward reach frame and arranged in a V with its apex pointing rearward, said blades being obliquely inclined to present a relatively sharp cutting edge to obstructions in the path, and spreader blades carried by the rear frame in V form with the 100 apex pointing forward, said spreader blades being arranged in slightly higher position than said planer blades to spread the removed material uniformly over the path. 95

4. In a grader, the combination with forward, rear and intermediate axles, of reach frames respectively connecting said forward and rear axle with said intermediate axle, and permitting universal pivotal connection between said frames, planer blades carried by said frame, spreader blades carried by said rear frame, hangers for supporting said blades independently adjustable to vary the height of the blade, and a common actuating mechanism for simultaneously raising or lowering all of said hangers to throw said blades out of or into work. 110

In testimony whereof I affix my signature.
WILLIS C. WARD.
